Primary Examiner—Carmen H. Vales-Lado

Attorney, Agent, or Firm—Wells, St. John, Roberts, Gregory & Matkin[57] **CLAIM**

The ornamental design for a portable long barrel firearm stand, as shown and described.

DESCRIPTION

FIG. 1 is a perspective view of a portable long barrel firearm stand showing my new design;

FIG. 2 is a top plan view thereof;

FIG. 3 is a right side elevational view thereof;

FIG. 4 is a left side elevational view thereof;

FIG. 5 is a bottom plan view thereof;

FIG. 6 is a front elevational view thereof;

FIG. 7 is a rear elevational view thereof;

FIG. 8 is a perspective view of a second embodiment of the portable long barrel firearm stand shown in FIG. 1; FIG. 9 is a top plan view thereof;

FIG. 10 is a right side elevational view thereof;

FIG. 11 is a left side elevational view thereof;

FIG. 12 is a bottom plan view thereof;

FIG. 13 is a front elevational view thereof;

FIG. 14 is a rear elevational view thereof;

FIG. 15 is a perspective view of a third embodiment of the portable long barrel firearm stand shown in FIG. 1;

FIG. 16 is a top plan view thereof;

FIG. 17 is a right side elevational view thereof;

FIG. 18 is a left side elevational view thereof;

FIG. 19 is a bottom plan view thereof;

FIG. 20 is a front elevational view thereof;

FIG. 21 is a rear elevational view thereof;

FIG. 22 is a perspective view of a fourth embodiment of the portable long barrel firearm stand shown in FIG. 1;

FIG. 23 is a top plan view thereof;

FIG. 24 is a right side elevational view thereof;

FIG. 25 is a left side elevational view thereof;

FIG. 26 is a bottom plan view thereof;

FIG. 27 is a front side elevational view thereof; and,

FIG. 28 is a rear elevational view thereof.
